D11-35.

OR D12,264

EX

UNITED STATES PATENT OFFICE.

GEORGE KREMENTZ, OF NEWARK, NEW JERSEY.

DESIGN FOR A FINGER-RING.

SPECIFICATION forming part of Design No. 12,264, dated May 17, 1881.

Application filed March 1, 1881. Term of patent 7 years.

To all whom it may concern:

Be it known that I, GEORGE KREMENTZ, of Newark, in the county of Essex and State of New Jersey, have invented a new and Improved Design for Finger-Rings, of which the following is a full, clear, and exact description.

This design relates to that class of rings provided with a head that does not rise out of the outer surface of the ring.

In my new design for finger-rings the shanks B B of the ring are ornamented at the ends with a leaf ornamentation, C, there being two half-leaves on the outside, and one or more full leaves arranged between them, all forming a continuous curve with the shanks and head of the ring.

The head or stone A may be flat or curved, but preferably forms one continuous curve with the shanks of the ring and the leaf ornamentation at the end of the same; but the surface of the head or stone proper must not rise out of the outer surface of the ring.

Having thus described my invention, I claim as new and desire to secure by Letters Patent—

A design for finger-rings, consisting of a leaf ornamentation, C, arranged on and forming a continuous curve with the shanks of a ring, as shown and described.

GEORGE KREMENTZ.
